DESIGN FOR A MERCHANTISE DISPLAY RACK

Harry S. Pakula, Chicago, Ill.

Application January 26, 1939, Serial No. 82,613

Term of patent 3½ years

To all whom it may concern:

Be it known that I, Harry S. Pakula, a citizen of the United States, residing at Chicago, in the county of Cook and State of Illinois, have invented a new, original, and ornamental Design for Merchandise Display Racks, of which the following is a specification, reference being had to the accompanying drawing, forming a part thereof.

In the drawing:

Figure 1 is a perspective view of the merchan-

dise display rack looking at the front thereof, showing my new design, and

Fig. 2 is a side elevational view thereof.

The rack is provided with a number of forwardly opening recesses for the reception of the merchandise to be displayed.

I claim:

The ornamental design for a merchandise display rack, substantially as shown and described.

HARRY S. PAKULA.
